UNITED STATES PATENT OFFICE.

HARRY C. WAY, OF NASHVILLE, TENNESSEE.

DESIGN FOR A GRAVE MARKER.

60,712.

Specification for Design. Patented Mar. 21, 1922.

Application filed May 4, 1921. Serial No. 466,704. Term of patent 7 years.

To all whom it may concern:

Be it known that I, HARRY C. WAY, a citizen of the United States, residing at Nashville, in the county of Davidson and State of Tennessee, have invented a new, original, and ornamental Design for Grave Markers, of which the following is a specification, reference being had to the accompanying drawing, forming a part thereof.

The figure is a perspective view of a grave marker showing my new design.

I claim:

The ornamental design for a grave marker as shown.

HARRY C. WAY.
